UNITED STATES PATENT OFFICE.

JOHN CLARK, OF BUFFALO, NEW YORK.

HOISTING HOOK.

Application filed May 26, 1925. Serial No. 32,962.

To all whom it may concern:

Be it known that I, JOHN CLARK, a citizen of the United States, residing at Buffalo, in the county of Erie and State of New York, have invented new and useful Improvements in Hoisting Hooks, of which the following is a specification.

This invention relates to a hoisting hook which is more particularly designed for use 10 in connection with hoisting tackle and machinery which lifts heavy loads from one place to another, such for example as freight, packages and structural material to and from a ship, railway car or wharf.

15 Hoisting hooks for this purpose as heretofore constructed were liable to become caught against obstructions either while ascending or descending and the same were also liable to release the load or become unlatched therefrom, thereby not only interfering with the progress of transferring the material from one place to another but also endangering the safety of the operatives.

It is the object of this invention to provide 25 a hoisting hook for this purpose which is not only stronger and more durable than those heretofore known but is also not liable to foul against adjacent obstructions and is also incapable of becoming detached from the load and thereby enable freight to be handled with maximum safety to the operatives and also without any delay due to possible interferences.

30 In the accompanying drawings:— Figure 1 is a side elevation of a hoisting hook which embodies a satisfactory form of my invention.

Figure 2 is a front elevation of the same. 35 Figure 3 is a vertical longitudinal section 40 of the same.

Figures 4 and 5 are horizontal sections taken on the correspondingly numbered lines in Fig. 3.

Figure 6 is an elevation of the tightening 45 or clamping bolt used in connection with this hoisting hook.

Similar characters of reference indicate like parts throughout the several views.

The main part or body of this hoisting 50 hook comprises an upright shank 10 and a forwardly and upwardly turned beak 11 at the lower end of this shank forming an upwardly opening mouth between this shank and beak which is adapted to receive the 55 ring, rope or other means whereby the load to be lifted is attached to the hoisting hook.

At its upper end the shank is provided with means whereby the same is connected to the hoisting mechanism. In the present instance this is accomplished by means of an 60 eye 12 which overhangs forwardly from the upper end of the shank and receives the lowermost link 13 of a hoisting chain forming part of the hoisting tackle or mechanism, such as that now in common use for this 65 purpose.

By overhanging the attaching eye 12 forwardly the center of gravity of the hoisting hook is brought nearly in line with the mouth of the hoisting hook so that the 70 weight of the load suspended by the hoisting hook will be forced to hang to a greater extent from the shank 10 and thereby relieve the beak 11 to a corresponding extent 75 from this load so as to reduce the liability of breaking the latter to a minimum.

For the purpose of still further increasing the strength of the beak, also to prevent accidental disengagement of the load from the mouth of the hoisting hook and also to prevent the hoisting hook from fouling or becoming caught against obstructions, the following means are provided:—

Movable into and out of a position across the mouth of the hoisting hook is a keeper or latch 14 which is preferably permanently connected with the upper part of the shank while its lower end is detachably connected with the beak of the hoisting hook so as to permit of opening and closing the mouth of the same. At its lower end this latch is provided with an inwardly and upwardly projecting hook 15 which in its operative position projects inwardly and upwardly through an opening 16 in the upper part of the beak 11. At its upper end the keeper 14 is provided with a curved lip 17 which is turned inwardly and downwardly and forms a rounded seat 18 on the underside of this lip and a rounded periphery 19 on the upper side of the same. This lip is also provided with a slot 20 extending vertically through the same from the under side to the upper side thereof.

On the upper part of the front side of the shank the same is provided with a forwardly projecting lug 21 which is formed integrally with the shank. This lug is provided with a vertical opening 22 which is preferably rectangular or square in cross section, as 110 shown in Fig. 4, for a purpose which will presently appear.

The numeral 23 represents the vertical body of the tightening or clamping bolt which has its central part made square in cross section and fitted in the opening 22 of the lug 21 so as to be capable of sliding vertically therein but incapable of turning therein, and the lower part of this bolt body is arranged within the slot 20 of the keeper so that the latter is also incapable of turning horizontally on this bolt body, this being accomplished by arranging the longitudinal sides of the slot parallel and close to the opposite flat sides of the bolt shank 23, as shown in Fig. 5. At its lower end the bolt body is provided with a horizontal cross head 24, which is of cylindrical form in cross section and engages its opposite end with the rounded under side 18 of the lip 17, thereby permitting the keeper 14 to swing on this 10 tightening bolt in a vertical plane parallel with the plane of the shank and beak of the hoisting hook.

The under side of the lug 22 adjacent to the periphery of the coupling lip 17 is preferably of round or concave form, as shown at 25, and the upper side of this lug is preferably flat, as shown at 26.

The numeral 27 represents a clamping screw nut applied to the upper externally threaded end 28 of the bolt body and bearing with its under side against the flat top 26 of the lug 21. This screw nut is prevented from becoming wholly unscrewed or detached from the body of the tightening bolt by a stop device which preferably consists of a stop disk 29 overhanging the sides of the bolt body and secured to the latter by means of a screw 30. In order, however, to permit the screw nut to be unscrewed from the bolt body a sufficient extent to release the keeper and still avoid making the bolt body unduly long the upper side of the screw nut is provided with a recess 31 which, in the fully unscrewed position of this nut, receives the marginal part of the stop disk 29, as shown by dotted lines, in Fig. 3.

Preparatory to attaching this hoisting hook to a load the screw nut 27 is loosened by unscrewing the same and permitting the bolt body to drop, thereby relieving the upward pull on the keeper 14 and enabling the latter to be swung outwardly at its lower end for disengaging the hook 15 therefrom in the opening 16 in the upper end of the beak 11. In Fig. 3 the latch is represented by dotted lines in a position in which it is only swung outwardly part way, but in Fig. 1, the latch is represented by dotted lines as having been swung outwardly and upwardly into its fully open position in which the mouth of the hoisting hook is completely uncovered and permits of introducing a ring, rope or other means of attachment on the load to be passed into or out of the mouth of the hoisting hook.

After the ring or other attaching means on the load has been inserted in the mouth of the hook the keeper or latch 14 is swung downwardly and engaged with its hook 15 in the opening 16 in the beak 11 and then the screw nut 27 is tightened so as to cause an upward pull of the bolt body 23 on the keeper. By this means the keeper is firmly and reliably interlocked at its lower end with the beak 11 so as to prevent accidental disengagement therefrom and the beak is also connected with the upper part of the shank 10, whereby the beak is supported and reinforced and will virtually convert the hoisting hook into a closed link and enable the hoisting hook to carry a load approximating that capable of being carried by a closed link. While thus moving the keeper into and out of its operative position the same can only swing in a vertical plane parallel with the plane of the shank and beak of the hoisting hook, this being due to engaging the body of the tightening bolt which is square in cross section with the correspondingly shaped opening 22 and slot 20 in the lug 21 and lip 17 of the shank and keeper, whereby the latter is prevented from turning horizontally or in a plane at right angles to the plane of the shank 10 and beak 11.

The clamping bolt together with its nut and the lug in which the same is mounted are arranged almost wholly underneath the adjacent overhanging part of the inwardly attaching eye 12 of the shank 10, and the keeper or latch 14 forms a substantially even surface from the tightening means to the beak 11, thereby presenting no pronounced shoulders or surfaces on the exterior of the hoisting hook which are liable to be caught on other objects, thereby preventing the hoisting hook from becoming fouled either while loading or unloading freight or similar material and expediting this work and reducing the cost of the same accordingly.

Inasmuch as the keeper is positively locked across the mouth of the hook when the same is tightened or in its operative position this positively prevents the load which is being transported from becoming accidentally detached from the hoisting hook and thereby prevent injury to the operatives which otherwise would be liable to occur.

Furthermore all of the several parts of this hoisting hook and the closure means for the mouth of the same are permanently connected so that it is impossible for any of the parts to become detached and lost but instead maintains this hook and its attachment always in a condition ready for use. The tightening and loosening of the clamping nut 27 can be effected by turning the same either by means of an ordinary wrench applied to the flat facets 32 on the periphery of this nut or by inserting a wrench rod

or pin into one or another of the openings 33 formed in the periphery of this nut, as shown in Figs. 1 and 2.

As a whole this hoisting hook is comparatively simple and compact in construction, it is very strong and durable and not liable to give way under the load imposed upon the same, and it can be used in connection with any of the well known or standard 10 forms of hoisting apparatus or tackles now in common use.

I claim as my invention:—

1. A hoisting hook having a shank provided on its front side with a lug and a beak 15 provided with an opening, a tightening bolt mounted lengthwise on said lug, and a keeper movable into and out of a position across the mouth of said hook and pivoted at one end on said bolt and provided at its 20 opposite end with a hook adapted to engage with said opening of the beak.

2. A hoisting hook having a shank provided on its front side with a lug and a beak 25 provided with an opening, a tightening bolt mounted lengthwise on said lug and provided on its inner end with a cross head and on its outer end with a screw nut adapted to engage with the outer side of said lug, and a keeper movable into and out of a position 30 across the mouth of said hook and provided at one end with an opening which receives said bolt between the head thereof and the inner side of said lug and provided at its opposite end with a hook adapted to engage 35 with the opening of said beak.

3. A hoisting hook having a shank provided on its front side with a lug and a beak 40 provided with an opening, a tightening bolt mounted lengthwise on said lug, and provided on its inner end with a cross head and on its outer end with a screw nut adapted to engage with the outer side of said lug, a keeper movable into and out of a position 45 across the mouth of said hook and provided at one end with an opening which receives said bolt between the head thereof and the inner side of said lug and provided at its

opposite end with a hook adapted to engage with the opening of said beak and means for preventing said screw nut from being 50 wholly removed from said bolt.

4. A hoisting hook having a shank provided on its front side with a lug and a beak 55 provided with an opening, a tightening bolt mounted lengthwise on said lug and provided on its inner end with a cross head and on its outer end with a screw nut adapted to engage with the outer side of said lug, a keeper movable into and out of a position 60 across the mouth of said hook and provided at one end with an opening which receives said bolt between the head thereof and the inner side of said lug and provided at its opposite end with a hook adapted to engage with the opening of said beak and means 65 for preventing said screw nut from being wholly removed from said bolt consisting of a stop disk arranged on the outer end of said bolt and projecting beyond the sides thereof, and a screw connecting said bolt 70 and disk.

5. A hoisting hook comprising a shank provided on its inner side with a lug having a rounded under side, a flat outer side and a longitudinal opening which is square 75 in cross section and a beak provided with an opening, a longitudinal tightening bolt having a square body arranged in said square opening, a round cross head at its inner end and an external screw thread at its 80 outer end, a screw nut arranged on the threaded outer end of said bolt and adapted to bear against the flat outer side of said lug, and a keeper movable into and out of a position 85 across the mouth of said hook and having a curved upper lip which is arranged between the rounded underside of said lug and the round head of said bolt and provided with a parallel sided slot which receives the body of said bolt and said keeper being provided at its lower end with a hook adapted to engage with the opening of 90 said beak.
